GRIP CLAW HAMMER

Menne Nieuwsma, Herreid, S. Dak.

Application July 23, 1948, Serial No. 40,339

3 Claims. (Cl. 254—26)

1

This invention relates to claw hammers, and particularly to a grip claw hammer having means for increasing the effectiveness and range of the use thereof.

The main object of my invention is to provide a claw hammer with means for increasing the capacity thereof for removing long nails, and provide an improved grip thereon.

Another object is to provide a claw hammer with an auxiliary member which serves to engage simultaneously with a nail when also engaged by the claw equipment of the hammer, for obtaining a sure grip upon the nail.

A further object is to have such a hammer provided with an integral ring or yoke member spaced within the claws of the hammer for bending and biasing a nail into effective gripping relation with said jaws.

An object of the invention is also to have a claw hammer so self-contained and equipped that it is capable of drawing even long and tough nails in two stages, first, to start the nail, and then to draw it completely out.

It is likewise an object to produce a special claw hammer, as already outlined, which is practical, durable and uniformly effective to draw nails of substantially any size or length without using blocks beneath the claws, and which is also capable in every way of normal use as an ordinary claw hammer.

Other objects and the advantages of my invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a side elevation of a claw hammer made according to the invention and embodying the same in a practical form, the hammer being in proper position for drawing a long nail while a portion of the handle only is shown in order to reduce the view to reasonable proportions;

Figure 2 is an elevation of the hammer head of the hammer also shown in Figure 1, as seen from the inner or handle end in order to display the relations between the parts thereof;

Figure 3 is a vertical section taken on line 3—3 in Figure 2.

The same reference numerals are used to indicate the same parts throughout these views.

To carpenters, workmen and others who have occasion to use claw hammers, it is a familiar experience to find that the hammer is only capable

2

of starting the withdrawal of a nail, so that a block of wood must be placed under the hammer to pull the nail the rest of the way out. This situation is usually accepted as necessary, inasmuch as no means has been adopted generally to avoid such expedients. However, after considering this problem, it has occurred to me that a claw hammer should be permanently equipped with means thereon for facilitating the use of the hammer not only for starting the withdrawal of a nail, but also for pulling it completely out, and as a result I have succeeded in evolving a special claw hammer with self-contained means for starting and also fully withdrawing any nail which the claws thereof are capable of engaging, as will now be set forth in detail.

Hence, in the practice of my invention, and referring again to the drawing, the handle 4, which is only partly shown, projects in more or less conventional manner into a hammer head socket 5 of a hammer head generally indicated at 6, and having a conventional hammer anvil 7, while upon the opposite side or end of the hammer head are a pair of more or less conventional claws 8, 8, as best seen in Figure 2, with a wedge-shaped opening 9 therebetween. The claws 8, 8 are externally curved into conventional arcuate form and are therefore capable of engaging beneath the head of a nail, as indicated in broken lines at 10 in Figure 1.

Upon the hammer head intermediate the outer end 11, carrying the hammer anvil 7, and the claws 8, 8, and the inner end 12 of the socket 5, is integrally mounted a yoke or ring member generally indicated at 13, consisting of a pair of side arms 14, 14 which are arched rearwardly of the claws 8, 8 and at their outer ends united by means of an integral cross-piece 15 which is located a shorter distance from the socket 5 than the outer tips or ends of the claws 8, 8.

The arrangement is such that, viewing Figure 1 for example, the hammer is placed with the head 6 thereof in such position that the claws 8, 8 will straddle the nail 10 by the latter projecting up through the wedge-shaped slot 9 between them and the handle 4 thrown to the right so that the head 10 of the nail to be drawn is started and pulled a distance out from the wood or other material 16. Assuming that the nail has been pulled sufficiently far out to bring the head thereof above the point at which the claws 8, 8 are further effective, the head is removed momentarily and the yoke or ring portion 13 disposed about the shank 17 of the nail shown in full lines, and the claws again being brought to bear by means

of handle 4, the nail shank 17 will be engaged by the interior portion 18 of the cross-member 15 and thereby wedged between the claws 8, 8 to render positively effective the wedging grip of these claws upon the nail, even to the point of bending the nail as indicated at 19, when it will be found that the claws will grip the nail shank sufficiently to be effective to pull the nail the entire distance out of the wood 16. The cross-piece 15 is thus effective to bias the nail into effective contact with the claws so that it is entirely unnecessary for either the claws or any part of the yoke to engage beneath the head 19 of the nail shown in full lines in order to effect removal of the nail.

Obviously, the hammer head thus provided with biasing means for forcing a nail into effective gripping relation with the claws of the hammer may be made in several sizes and different proportions, and it is also true that the actual form of the claws and even of the yoke member 13 may be varied to suit conditions.

Manifestly, variations may be resorted to and parts and features may be modified or used without others within the scope of the appended claims.

Having now fully described my invention, I claim:

1. In a grip claw hammer comprising a hammer head having a handle socket adapted to receive a handle, a hammer anvil upon one portion and a pair of rearwardly-directed nail-pulling claws upon another portion, the improvement which includes a closed yoke or ring member rigidly mounted upon the hammer head and projecting independently rearward intermediate the claws and the handle end of the handle socket at a generally-inclined angular position with respect to the latter and including upon the outer extremity thereof a transverse portion spaced from said socket and the free ends of the claws in effective position to bias the nail into which gripping relation with said claws and said yoke or ring member surrounds the nail and the transverse portion thereof engages with the far side of said nail remote from the handle socket.

2. In a grip claw hammer comprising a hammer head having a handle socket adapted to receive a handle, a hammer anvil upon one portion

and a pair of rearwardly-inclined nail-pulling claws upon another portion, the improvement which includes a closed yoke or ring member rigidly mounted upon the hammer head intermediate the handle and the end of the handle socket and the claws, said yoke or ring member including a pair of integral arms projecting freely and independently rearwardly intermediate the claws and the handle socket at a generally-inclined angular position with respect to the latter, and a transverse cross-piece integrally connecting the outer ends of said arms and disposed intermediate the free ends of the claws and the handle end of said handle socket in effective position to bias a nail into wedged gripping relation with said claws when said yoke envelops the nail with said cross-piece engaging against the latter.

3. In a grip claw hammer comprising a hammer head having a handle socket adapted to receive a handle, a hammer anvil upon one portion and a pair of rearwardly-directed arcuate nail-pulling claws upon another portion, the improvement which includes an arcuate closed yoke or ring member integrally mounted upon the hammer head intermediate the handle end of the handle socket and the claws and comprising a pair of integral curved arms freely directed arcuately rearward intermediate the claws and the handle socket at a generally-inclined angular position with respect to the latter, and a transverse cross-piece integrally connecting the outer free ends of said curved arms and disposed intermediate the free ends of the claws and the handle end of the handle socket in effective position to bias a nail into wedged gripping relation with said claws when said yoke envelops the nail while said cross-piece engages against the latter.
